UNITED STATES PATENT OFFICE

115,230

DESIGN FOR A HAMPER OR SIMILAR ARTICLE

Harold Gleitsman, New York, N. Y.

Application February 4, 1938, Serial No. 74,867

Term of patent 14 years

To all whom it may concern:

Be it known that I, Harold Gleitsman, a citizen of the United States, residing in New York city, in the county of New York and State of New York, have invented a new, original, and ornamental Design for a Hamper or Similar Article, of which the following is a specification, reference being had to the accompanying drawing, forming part thereof.

The figure is a perspective view of a hamper or similar article embodying my new design.

The dominant features of the design reside in the portions shown in solid lines.

The side and end portions opposite to those shown in the drawing have substantially the same appearance as those shown.

I claim:

The ornamental design for a hamper or similar article, as shown and described.

HAROLD GLEITSMAN.
